TIPPING MECHANISM.

1,393,524.

Specification of Letters Patent. Patented Oct. 11, 1921.

Application filed July 12, 1919. Serial No. 310,361.

To all whom it may concern:

Be it known that I, WILLIAM F. GRUPE, a citizen of the United States of America, residing at Hudson Heights, county of Bergen, State of New Jersey, have invented 5 certain new and useful Improvements in Tipping Mechanism, of which the following is a specification.

This invention relates to tipping machines 10 and more particularly to apparatus for affixing tipping material such as cork, or equivalent, at spaced locations on a strip of paper, or equivalent material, desirable for use in the manufacture of cigarettes, or like products.

An object of the invention is to provide 15 means for effectually affixing the tipping material, preferably by continuous feed. Further features of the invention comprise 20 providing by continuous feed an indefinite length of the tipping material, severing the same to desired dimensions, applying adhesive thereto and effecting the affixing of the severed tipping material to the strip 25 of paper.

The invention is designed for use directly 30 with any approved type of cigarette making machine and is synchronized in operation therewith to discharge the tipped paper strip in operative relation to the cigarette making machine.

In accordance with my most preferred 35 form of the invention, the cork having the adhesive applied thereto is supplied to the paper strip at a time when the liquid constituent of the adhesive has sufficiently permeated into the cork and the adhering constituent is in mature condition, applying pressure to the supplied cork and paper under the condition of retarded progress of the 40 paper. Such arrangement when applied to a rod-forming type of cigarette making machine enables the paper strip to progress through the rod-forming mechanism of the 45 machine at the usual required uniform speed. Such correlation of my tipping mechanism with a rod-forming cigarette machine is effected by the provision of means for retarding the paper to approximately the rate 50 of supply of the tipping material.

Preferably, the cork is fed as a continuous strip of indefinite length, cut to the desired dimensions, adhesive having been applied to the cork under conditions to insure proper

condition of the adhesive, while maintaining 55 the apparatus free from adhesive, feeding such adhesive-applied cork portions in proper relation to a strip of paper, affixing the cork portions successively to the strip of paper at desired spaced intervals thereon, 60 and discharging the resulting product in suitable relation to a cigarette-making machine.

Further features and objects of the invention will be more fully understood from the 65 following description and accompanying drawings, in which—

Figure 1 is a diagrammatic side elevational view partly broken away in central vertical section, showing a preferred form 70 of apparatus embodying my invention;

Fig. 2 is a sectional elevation of the retaining drum on line 2—2 of Fig. 1;

Fig. 3 is a detail perspective view of an upper portion of the retaining drum, broken 75 away to indicate inner construction;

Fig. 4 is a diagrammatic, perspective view showing the retaining drum and other parts of Fig. 1; and

Fig. 5 is a top plan view of the arrangement of Fig. 1, with parts omitted;

Fig. 6 is one form of the resulting product; and

Fig. 7 is a diagrammatic view of a modified form of the invention.

In the specific form of the invention as shown in Fig. 1, the cork is supplied in indefinite length in a continuous manner, as by a rotary drum, severing therefrom desired lengths, thereafter applying adhesive 90 of suitable character to the cork, conveying the adhesive applied, severed cork portion for a determined interval to condition the adhesive, feeding a strip of cigarette paper in close adjacency to the successively fed 95 cork portions, applying pressure to successively affix the portion to the strip of paper in a certain relation and synchronizing the resulting tipped paper strip in feeding relation to the cigarette making machine. 100

In the particular apparatus shown in the drawings, the reel of cigarette paper is indicated at 1, its end 2 being fed in the direction of the arrow 3.

The reel of cork is indicated at 4, its end 10 5 being fed in the direction of the arrow 6, over the roller 7, thence over the roller 8, thence in the direction of the arrow 9 be-

tween the sustaining drum 10 and the coacting severing drum 11.

As is indicated in Fig. 5, the severing drum 11 and the sustaining drum 10 may be mounted on a common frame 12, in which is also mounted suitable gearing for driving said drums 10, 11 in suitable relation to effect the purpose of the invention. In the specific form of gearing and mounting 5 means shown in Fig. 5, the power shaft is indicated at 13, suitably mounted (not shown), on which is fixed the gear 14 meshing with the main gear 15, fixed on the shaft 16, to which is fixed the sustaining drum 10 by means of the key 17, or equivalent. Fixed also on the shaft 16 is the large gear 18 meshing with the relatively small gear 19, fixedly mounted on the shaft 20 to which is also fixed the severing drum 11, as by 10 means of the key 21, or equivalent.

The sustaining drum 10 is preferably of the pneumatic, *i. e.*, suction type, and for such purpose is provided with peripheral retaining means comprising the passages 22 15 communicating with the interior of the drum 10, in turn communicating with a suitable air discharge outlet 24 connected with a suitable pneumatic, *i. e.*, suction, apparatus. In the particular form of the invention shown in the drawings, a rotary type 20 of cork retaining means is shown and the parts so arranged that the larger portion of the peripheral surface of the sustaining drum is effectively employed, the non-effective 25 position being provided with suitable means for obviating loss of air. The drum proper 10 is formed of a separable portion 25 having a substantially cylindrical peripheral face 26 to which extend the inlets of the 30 respective passages 22, said portion 25 having the outer peripheral annular edge 27 adapted to be sealingly seated on the face 28 of the disk 29, provided with the boss 30. The disk 29 is fixedly supported on the frame 12 by means of bolts or screws 32, the inner 35 cylindrical face of the boss 30 forming a snug fit in sealing relation with the shaft 16. Such disk 29 is provided with the inwardly disposed arcuate flange 33, see Figs. 1 and 2, extending for the extent of non-effective rotation of the air passages 22, as is indicated in Fig. 1. The severing drum 11 is indicated in Figs. 1 and 3, the latter being on a somewhat enlarged scale, and 40 comprises a plurality of spaced individual severing means in the form of blades 35, each blade having a chisel edge extending normal to the direction of travel of the drum 11. Each blade 35 is provided with oppositely 45 disposed shoulders 37, and with suitable resilient pressure means such as springs 38, suitably adjusted for determining the desired severing pressure, dependent upon the character and condition of the cork, the humidity of the air at the time of operation

and other circumstances, as I have discovered. The severing drum 11 is provided also with the oppositely disposed peripheral rings 39, coacting with the shoulders 37.

The springs 38 are preferably arranged in balanced relation to each blade 35, as in pairs, countersunk in the recesses 40, the extent of projection of each blade 35 beyond the peripheral face 41 of the cutting drum 11 being determined by the rings 39 coacting with the shoulders 37. The individual knives 35, usually having chisel-shaped blades, are arranged on the severing drum, of suitable diameter and relation to the retaining drum, to effect a severing of the cork within a predetermined microscopic distance from the unexposed face of the cork, the resulting severed cork portions being retained on the retaining drum 11 so that the abutting severed edges of the succeeding severed cork portions are sufficiently close to preclude leakage or escape of the adhesive to the operating face 26 of the retaining drum 10, thereby maintaining the retaining drum free from adhesive, obviating waste of material and maintaining the severed cork portions free from one another.

In the arrangement shown in Fig. 1, the application of the adhesive to the cork is performed at a stage subsequent to the stage 95 of severing, in which arrangement provision of means is made for the proper extent of travel of the cork subsequent to applying of adhesive to properly condition the adhesive, as appears more fully hereinafter.

The cork portions are supplied with adhesive by suitable adhesive supplying means, such as comprising the fountain 45 adapted to contain suitable adhesive 46, conveyed by the feed roll 47 and the applying roll 48, 105 mounted in suitable bearings carried by the fountain 45. The feed roll 47 is shown having a portion of its cylindrical face extending into the adhesive and its flat ends arranged in sealing relation with the side walls 110 of the fountain 45. The bottom of the fountain is tapered with a minute clearance relative to the cylindrical face of the feed roll 47, to effect a coating of the adhesive of the desired thickness, to be conveyed to the applying roll 48. The applying roll 48 is positively driven, as by the gearing driven from the drive shaft 15, or other suitable means. The applying roll 48 extends in suitable adjacency to the location 49 in the 120 path of travel, *i. e.*, the operating face 26, of the successive cork portions, to apply adhesive to their exposed faces.

Each cork portion is progressed through a sufficient path of travel to insure proper 125 conditioning of adhesive on the face of the cork and proper "wetting" of the cork, as is provided by the extent of travel of the retaining drum 10 from the location 49 to the location 50, at which latter location the cork 130

portions are successively affixed to the lower face of the strip of paper 2.

Suitable affixing means comprises the tamping pad 51 (see Figs. 1 and 4), mounted on the plate 52, suspended from the arm 53, pivotally carried by the pressure arm 54 controlled by the cam 55. The cam 55 (see Fig. 5 also) is mounted on the aforesaid shaft 16.

10 The cam 55 is provided with spaced cam recesses 56, co-acting with the pin 57, carried by the oscillating arm 58, fixed to the shaft 59, pivotally mounted on the frame 12. The pressure arm 54 is fixed to the oscillating 15 shaft 59 and is tensioned by the retractile coiled spring 60, suitably adjusted in effective pressure and having its fixed end attached to the frame 12, or other suitable fixed support. The pivotal mounting of the 20 arm 53 on the pressure arm 54 is preferably by means of the shaft 64 rotatively mounted in the bearing 65, at the free end of the pressure arm 54, and resiliently connected to the pressure arm 54 by means of the arm 65^a, receiving one end of the retractile spring 66, its other end being carried by the arm 67, projecting fixedly from the pressure arm 54. The arm 53 is adjustably mounted on the shaft 64, as by the head piece 68, provided 25 with an opening (see Fig. 4), through which the end of the arm 53 projects and with the set screw 69. Such universal mounting of the tamping plate 51—52 provides for accommodation of the plate 52 to the different thicknesses, or variations of thickness of the cork and paper, and for self-adjustment of the plate to the operating face of the rotating drum 10 during the stage of exerting pressure on the cork portions 44 and the relatively delicate paper strip, while allowing 30 the drum 10 to continue its movement.

40 The paper strip 2 having the tips applied on its lower face progresses in the cigarette making machine along the path indicated by the arrow 61, under the usual action of the tube belt or forming band (not shown) of the cigarette making machine, the tobacco being fed from a suitable hopper onto the upper face of the paper strip 2. The tube belt passes through the usual forming shoe of the cigarette making machine to roll the paper strip 2 and tobacco to form the cigarette rod.

45 In Fig. 6 the resulting product is indicated as comprising the tip 44 of double size of the tip of a single cigarette and in such case, the cigarette rod is severed by suitable severing means on a line corresponding to the dash line 75 (see Fig. 6) through the tipped portion 44, the paper strip 2 and the contained tobacco and a line corresponding to the line 76 through the paper strip 2 and the contained tobacco to form the individual cigarettes.

50 35 I have discovered that the severing of the

cork may be advantageously performed after the adhesive has been applied thereto, and in Fig. 7 I have indicated a suitable arrangement for carrying out such method. As shown, the adhesive fountain 70, corresponding in its parts to the aforesaid fountain 45, like parts being designated by like reference numbers, is positioned along the travel of the cork retaining drum 10 in advance of the severing drum 71, having the 75 severing blades 35 and otherwise constructed similar to the aforesaid severing drum 11.

For the purpose of providing for the uniform feeding of the tipped paper strip by the tube belt through the forming shoe or 80 other rod-forming mechanism, of the cigarette making machine, and at the same time permit the momentary interruption or retardation of the paper strip 2 during the stage of affixing the cork portions 44 thereto, 85 I have arranged the loop or slack providing means comprising the oscillating arm 75 (see Figs. 1 and 4) pivoted at 76 and controlled by the cam 77 through the bell crank 78. The cam 77 is suitably driven in the direction of the arrow 63 by its shaft 79 in synchronism with the cam 55, controlling the pressure plate 52. The cam face of the cam 77 is provided with the projecting portion 80 and timed to engage the roller 81 of 90 the bell-crank 78, to oscillate the bell-crank 78 and move the arm 75 upwardly from its position shown by full lines in Fig. 1, to its position 83 shown in dotted outline to let out the loop or slack 82 during the stage of 100 engagement of pressure plate 52 with the paper strip 2, whereas the remainder 84 of the cam face is substantially circular and depressed relative to the projecting portion 80, and under the action of the retractile spring 95 85, the arm 75 is moved to provide the loop or slack 82.

Similar loop or slack forming means may be provided anterior of the location 50, as is indicated at the right in Fig. 1 and comprising the arm 90, pivoted to the frame at 91, and oscillated in synchronism with the tipping device to form the loop or slack during the stage of engagement of the plate 52 with the paper strip 2, and thereby maintain the reel 1 of paper in motion during the stage of retardation of the portion of the paper strip 2, held under the plate 52. A convenient form of actuation is by means of the link 92 connecting the anterior looping arm 90 with the posterior looping arm 75 and arranged to move the arm 90 to its looping position, indicated in dotted outline 93 when the arm 75 is moved to its non-looping position 83, and vice versa.

110 120 125 The invention is particularly applicable for direct use with an approved type of cigarette making machine, to which the resulting tipped paper strip is fed, and the operations of the tipping machine are syn-

chronized therewith. To this end, the aforesaid shaft 13 may be any suitable shaft of the cigarette making machine.

5 The scraper 94 is provided for removing any cork passing beyond the location 50.

Guides 95 are provided for laterally guiding the paper strip 2. It will be noted that the advance arrangement of the adhesive applying means relative to cork severing 10 means shown in Fig. 7, permits the cork retaining drum 10 to be formed of small diameter for the use of the same or similar character of adhesive, to provide for an given absolute path of travel of the adhesive through the air for conditioning the same, whereas in the arrangement shown in Fig. 4, the conveying drum is of relatively larger diameter to provide for an equal path of travel.

20 Whereas I have described my invention by reference to specific forms thereof, it will be understood that many changes and modifications may be made without departing from the spirit of the invention, as defined 25 by the appended claims.

I claim—

1. The combination of means for progressing a strip of paper, means for supplying tipping material, said two means operating at different speeds, means for applying under pressure the supplied tipping material to the paper strip and means for substantially equalizing the speed of the portion of the paper strip to which the 35 tipping material is being applied to the speed of supply of said tipping material.

2. The method of forming tipped cigarette paper comprising progressing the paper as a continuous strip at a certain speed, progressing toward said strip tipping material at a different speed, applying pressure to the tipping material while in contact with a portion of the paper strip and substantially equalizing the speed of such portion 45 of the paper to which the tipping material is being applied to the speed of the tipping material during the stage of applying pressure.

3. The method of forming tipped cigarette paper comprising progressing the paper as a continuous strip at a predetermined speed, supplying under pressure the tipping material to the paper strip and at a less speed and substantially reducing the 55 speed of the portion of the paper strip to which the tipping material is being applied to the speed of supply of said tipping material supplying means.

4. The combination with means for progressing a strip of paper continuously at a substantially constant speed, means for supplying tipping material in successively delivered portions at a different speed, means for applying under pressure the individual portions of tipping material to the

paper strip and means for substantially equalizing the speed of the portion of the paper to which the portion of the tipping material is being applied to the speed of delivery of the tipping material.

5. In the combination with a cigarette making machine having rod forming mechanism and means for supplying a strip of paper to said rod forming mechanism at a substantially constant speed, means for supplying tipping material to the paper strip at a different speed, means for applying under pressure the supplied tipping material to successive portions of the paper strip and means for substantially equalizing the speed of such successive portions respectively of the paper strip to the speed of supply of the tipping material.

6. The method of supplying tipping material to a cigarette making machine provided with rod forming mechanism including a tube belt, means for operating the tube belt and means for supplying the paper strip at a substantially constant speed, comprising feeding the tipping material to successive portions of the paper strip at a less speed, applying pressure to the successive portions of the tipping material while in contact with the paper strip and reducing the speed of the portion of the paper strip 95 while under such pressure to the speed of the feeding of the supplied tipping material.

7. In combination with a cigarette making machine, comprising rod forming mechanism including a tube belt, means for operating said tube belt and a support for a reel of paper to be fed to said tube belt, of tipping mechanism comprising rotary means for feeding the tipping material in successive portions, means for rotating said feeding means at a speed less than the speed of the paper, means for applying pressure to the fed portions of tipping material while in contact with the paper strip and means for compensating the speed of the portion of the paper strip while under pressure to the speed of supply of the tipping material, said compensating means comprising members for displacing spaced portions of the paper strip on opposite sides of said pressure means and means for oscillating said displacing members inversely to the paper strip.

8. In combination with a cigarette making machine, comprising rod forming mechanism including a tube belt, means for operating said tube belt and a support for a reel of paper to be fed to said tube belt, of tipping mechanism comprising substantially cylindrical means for feeding the 125 tipping material, means for moving said cylindrical means at a speed different from the speed of the paper and substantially cylindrical means for applying pressure to the tipping material while in contact with 130

the paper strip and means for compensating the speed of the portion of the paper strip while under pressure relative to the speed of supply of the tipping material.

- 5 9. The combination with substantially circular feeding means, of a substantially circular pressure applying means coacting therewith, a loop-forming element disposed anteriorly of said feeding means and said 10 pressure applying means, a loop-forming element disposed posteriorly of said feeding means and said pressure applying means, means for moving said loop-forming elements from their respective loop forming 15 positions to their non-loop-forming positions inversely, and means for continuously moving said cylindrical feeding means.

10. The combination of a cigarette making machine; a tipping device comprising a 20 drum adapted to receive and retain cork of indefinite length; rotary severing means coacting therewith for severing the cork to desired dimensions; said severing means comprising a circular element; spaced individual severing blades, resilient means tending normally to force said blades beyond the circular periphery of said circular element and means for limiting the extent of outward movement of said blades; and means 25 for feeding the tipped paper strip to said cigarette making machine at a substantially uniform rate.

11. In a tipping mechanism, substantially cylindrical means for feeding cork, means 30 for rotating said feeding means, adhesive supplying means, severing means, substantially cylindrical pressure applying means disposed proximate said feeding means at a certain location, adhesive supplying means 35 being disposed anteriorly at said certain distance to permit the supplied adhesive to become conditioned, a loop forming element disposed posteriorly of said pressure applying means, and means for moving said loop 40 forming elements alternately into and out of loop forming positions.

- 45 12. The combination of a cigarette mak-

ing machine; a tipping device comprising means for feeding a length of cork, a drum having a face adapted to receive said cork, 50 pneumatic means for retaining the cork on said face, means for severing the cork into portions of desired dimensions, means for supplying adhesive to the severed cork portions, means for feeding a strip of paper in 55 suitable adjacency to a certain portion of said drum, said certain portion being disposed at an appreciable distance from said adhesive supplying means, means for rotating said drum, means for exerting pressure on the successively fed cork portions and said strip of paper, and means for controlling the period of operation of said pressure exerting means.

13. In a machine for applying tipping 60 material to cigarette paper, the combination of a drum for carrying a strip of tipping material, a rotatable member, knives for severing the strip radially carried by and projecting from said drum, said drum and said 65 member being mounted in relatively fixed bearings, and resilient mountings for the knives to project the same at a distance in excess of that separating the adjacent surfaces of said drum and of said member to 70 compensate any variation in the extent of projection of the individual knives.

14. The combination with a cigarette 75 making machine, of means for supplying a strip of paper, means for supplying a length 80 of tipping material, means for severing said tipping material, means for affixing the severed tipping material to the strip of paper, means for looping the strip of paper anterior 85 of said affixing means, means for looping the tipped strip of paper posterior of said affixing means and means for driving said 90 supplying means, said severing means and said looping means to maintain a substantially constant feed to the cigarette making machine.

In testimony whereof I have signed this specification this 3rd day of July, 1919.

WILLIAM F. GRUPE.
